US00D891158S

(12) **United States Design Patent** (10) **Patent No.:** **US D891,158 S**
Gady et al. (45) **Date of Patent:** **** Jul. 28, 2020**

(54) **PRODUCT DISPLAY UNIT**

- (71) Applicant: **Apple Inc.**, Cupertino, CA (US)
- (72) Inventors: **Jean-Marc Gady**, Los Altos, CA (US); **Seung Chae Kang**, New York, NY (US); **Gabriel J. Lamb**, Burlingame, CA (US); **Adrian E. Magrina**, San Francisco, CA (US); **Indhu V. Solayappan**, Sunnyvale, CA (US); **Moritz Wilsberg**, Menlo Park, CA (US)

- (73) Assignee: **Apple Inc.**, Cupertino, CA (US)

- (**) Term: **15 Years**

- (21) Appl. No.: **29/693,874**

- (22) Filed: **Jun. 5, 2019**

- (51) LOC (12) Cl. **06-06**

- (52) U.S. Cl.

USPC **D6/682.1**

Primary Examiner — Kelley A Donnelly*(74) Attorney, Agent, or Firm* — Sterne, Kessler, Goldstein & Fox P.L.L.C.(57) **CLAIM**

The ornamental design for a product display unit, as shown and described.

DESCRIPTION

FIG. 1 is a top front perspective view of a product display unit showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the product display unit that form no part of the claimed design.

1 Claim, 4 Drawing Sheets
